UNITED STATES PATENT OFFICE.

JOHN M. GUYNN AND JAMES S. PARMER, OF NEWPORT, ARKANSAS.

DESIGN FOR A TWIN BED-SPRING.

SPECIFICATION forming part of Design No. 29,631, dated November 8, 1898.

Application filed September 19, 1898, Serial No. 691,385. Term of patent 7 years.

To all whom it may concern:

Be it known that we, JOHN M. GUYNN and JAMES S. PARMER, citizens of the United States, residing at Newport, in the county of Jackson and State of Arkansas, have invented and produced a new and original Design for Twin Bed-Springs; and we do declare the following to be a full, clear, and exact description of the same, reference being had to the accompanying drawings and specification, forming a part thereof.

Figure 1 is a side elevation of our twin bed-springs. Fig. 2 is a top plan view of the same.

As shown in the drawings, the leading or material feature of our design consists of two coils A, of wire, having in each coil seven twists and at the lower end of each coil and integral therewith a straight portion provided

with an upright end B and at the upper end of each coil and integral therewith a flat surface consisting of the half-circles 1, the square ends 2, straight sides 3, and connecting rectangular end bends 4. The coils A are smaller at their center than at either end.

Having described our invention, what we claim as new, and desire to secure by Letters Patent, is—

The design for a twin bed-spring, as herein shown and described.

JOHN M. GUYNN.
